(CL. D44—9)

To all whom it may concern:

Be it known that we, Maurice J. Denn and Charles W. Stanton, citizens of the United States and residents, respectively, of Redondo Beach and Los Angeles, all in the county of Los Angeles and State of California, have invented a new, original, and ornamental Design for a Teacup, of which the following is a specification, reference being had to the accompanying drawings, forming a part thereof.

Figure 1 is a top plan view of a teacup, showing our new design;

Figure 2 is a bottom plan view;

Figure 3 is a side elevational view; and

Figure 4 is a rear elevational view thereof.

We claim:

The ornamental design for a teacup, substantially as shown.

MAURICE J. DENN.
CHARLES W. STANTON.
